UNITED STATES PATENT OFFICE

117,392

DESIGN FOR A LIP BRUSH

Gilsey Marion Cochran, Los Angeles, and John
Sokso, Southgate, Calif.

Application August 19, 1939, Serial No. 86,792

Term of patent 14 years

To all whom it may concern:

Be it known that we, Gilsey Marion Cochran and John Sokso, citizens of the United States, residing at Los Angeles and Southgate, respectively, county of Los Angeles, State of California, have invented a new, original, and ornamental Design for a Lip Brush, of which the following is a specification, reference being had to the accompanying drawing, forming a part thereof.

Figure 1 is a front elevational view of a lip

brush showing our new design with the brush in closed or inoperative position; Figure 2 is a similar view thereof with the brush in open or operative position.

We claim:

The ornamental design for a lip brush, as shown.

G. MARION COCHRAN.
JOHN SOKSO.
